UNITED STATES PATENT OFFICE.

ALBERT M. BURRITT, OF WATERBURY, CONNECTICUT, ASSIGNOR TO THE
A. BURRITT HARDWARE COMPANY, OF SAME PLACE.

FIRE-EXTINGUISHER.

SPECIFICATION forming part of Letters Patent No. 241,922, dated May 24, 1881.

Application filed April 4, 1881. (No model.)

To all whom it may concern:

Be it known that I, ALBERT M. BURRITT, of Waterbury, in the county of New Haven and State of Connecticut, have invented a new 5 Improvement in Fire-Extinguishers; and I do hereby declare the following, when taken in connection with the accompanying drawings and the letters of reference marked thereon, to be a full, clear, and exact description of the 10 same, and which said drawings constitute part of this specification, and represent, in—

Figure 1, a side view; Fig. 2, a longitudinal section.

This invention relates to an improvement in 15 that class of fire-extinguishers which consist of a finely-perforated tip attached to the nozzle or outlet of the pipe in a room, and so constructed that when an accidental fire in the room shall raise the temperature to a predetermined point the supply of water will flow 20 through the perforated tip and be distributed about the room in the form of spray, to extinguish the accidental fire.

One difficulty in this class of extinguishers 25 arises from the fact that sediment or foreign particles are liable to settle in the pipe at the plug, and when the supply is let on the sediment or particles enter the perforated distributor or tip, and to a greater or less extent clog 30 the perforations.

The object of my invention is to overcome this difficulty.

My invention consists in the arrangement 35 of a plug constructed so that one end presents a spherical shape in the water-way leading to the distributor and secured by solder or similar fusible metal, and so that when liberated by heat the plug will enter the perforated distributor, and because of its peculiar 40 shape will be made to move about within the distributor by the action of the water, and by such movements break up or remove obstructions over the perforations within the distributor.

45 A represents the nozzle, which is attached to the supply-pipe at the point where the discharge is desirable, and into the end of this nozzle a metal plug, B, is secured by a metal or material fusible at a low degree of tempera-

ture—that is to say, 100° to 150°—or substance 50 as caps or plugs are usually secured in such apparatus.

C is the tip or distributor, preferably of spherical form, chambered out or made hollow, and fitted to screw onto the outside of 55 the nozzle, and so as to inclose the plug B. The tip or distributor is perforated, as shown, so that water forced into the chamber will be discharged therefrom in the form of spray. The supply of water is supposed to be constant 60 against the plug B, the plug constructed hollow, with one end rounded or semi-spherical, leaving straight sides sufficient to make connection with the walls of the passage in which it is placed. The spherical end is preferably 65 arranged toward the water, so as to prevent the water from lying within the cup and close to the soldered sides, which would retard the effects of the heat.

Aside from the heat-retarding effect, the plug 70 might be arranged with the spherical end toward the distributor; or the plug may be made semi-spherical at both ends, with sufficient bearing at the sides to make the required connection with the walls; but in any case it 75 should be made hollow, so as to make it as light as possible, and yet sufficient to sustain the water-pressure.

If a fire occur near the point where this device is applied, the heat from the fire will 80 quickly fuse or destroy the connection between the plug and the walls of the water-way, so as to permit the plug to be forced outward, followed by a forced supply of water. The plug enters the distributor, and will by the 85 action of the water be kept in constant motion around the inner surface of the distributor, and by such motion will remove obstructions which may be over the perforations within the distributor.

90 From the foregoing it will be understood that I do not broadly claim a perforated distributor combined with a plug of fusible metal or secured by a fusible metal in the water-way, so that whenever the heat shall have risen to 95 a predetermined degree the plug will be liberated and pass into the distributor or elsewhere, and permit the water to flow outward

through the distributor, as such I am aware is not new; but

What I do claim is—

A fire-extinguisher consisting of a perforated distributor communicating with the water-way, combined with a metal plug constructed at one end to present a rounded or spherical

shape, secured in the water-way at the entrance to the distributor by a fusible connection, substantially as described.

ALBERT M. BURRITT.
